UNITED STATES PATENT OFFICE

2,671,523

SILENCER OR MUFFLER FOR ENGINE
EXHAUSTS OR THE LIKEGeorge Bromhead Walker, Fulham, London,
England

Application July 3, 1951, Serial No. 234,954

Claims priority, application Australia
July 14, 1950

1 Claim. (Cl. 181—49)

1

This invention relates to an improved silencer or muffler for engine exhausts or the like, and more particularly to an improved construction of the silencer or muffler described in the specification of my co-pending United States patent application Serial No. 144,060, filed February 14, 1950.

The object of the invention is to provide an improved construction of silencer or muffler which will have greater efficiency in use with lower back pressure and also is more convenient to manufacture.

According to the invention, the improved silencer or muffler comprises a casing of progressively increasing diameter from the inlet end, a hollow core member with closed opposite ends concentrically supported within the casing and co-acting with it to form an annular gas expansion space of progressively increasing area receiving the gases from the inlet end, and breather ports or openings in the core member to permit the exhaust gases to pass from the gas expansion space into the hollow core member. The core member functions as a gas accumulator to smooth out the pulsating pressures of the engine exhaust, the gas pressure accumulating in said hollow core member on the high pressure phase and being released through the breather ports or openings on the low pressure phase.

The silencer or muffler may also be provided with an outer casing and breather ports or openings may be formed in the casing to communicate with the interior of said outer casing, said ports or openings allowing the exhaust gases to also accumulate in the interior of the outer casing in the same manner as in the hollow core member.

The invention is more fully described aided by reference to the accompanying drawings wherein:

Fig. 1 is a longitudinal sectional view of the improved silencer or muffler according to one embodiment of the invention.

Figs. 2 and 3 are cross-sections taken on lines 2—2 and 3—3 of Fig. 1.

Fig. 4 is a longitudinal sectional view of the improved silencer or muffler according to another embodiment of the invention.

Fig. 5 is a cross-section taken on line 5—5 of Fig. 4.

In the construction shown in Figs. 1 to 3, the silencer or muffler has a casing 1 of progressively increasing diameter from the inlet end 2 and a hollow core member 3 concentrically supported within the casing and co-acting with it to form the annular gas expansion space 4 of progressive-

2

ly increasing cross-sectional area. The core member is of substantially cylindrical shape closed at both ends and is centralized and supported within the casing by means of a spider 5 at its rear end and radial fins 6 at its forward end. The fins 6 are rigidly secured as by welding to the core member and are adapted to engage the inner wall of the tapering casing with a wedge fit.

10 The rear end of the core member carries a screwed stud 7 which passes through a central hole 8 in the spider 5 and receives a washer 9 and clamping unit 10. The nut 10 may have an elongated or streamlined tail 11. The spider is secured by means of bolts 12 between flanges provided on the rear end of the casing 1 and a tapered outlet casing 13.

15 The forward end of the core member is provided with a tapered nose 14 which divides the gas stream entering the casing through the inlet end 2 into an annular stream as it passes to the gas expansion space 4. Rearwardly of said nose breather ports or openings 15 are formed in the core member to allow the exhaust gases to enter the hollow interior of the core member from the expansion space 4.

20 In use, the exhaust gases entering through the inlet end 2 of the casing 1 pass along the tapered nose 14 of the core member into the annular gas expansion space 4 between said core and the casing. As the cross-sectional area of the expansion space progressively increases, the exhaust gases expand in their passage and so become reduced in pressure.

25 30 35 The ports 15 in the core member allow the exhaust gases from the expansion space to enter the hollow core member which thus functions as a gas accumulator to smooth out the pulsating pressures of the exhaust. On the high pressure phase, the gas pressure accumulates in the hollow core member and is released on the low pressure phase. Thus, when the gases escape from the outlet they are greatly reduced in pressure and substantially free from pulsations. Noise is thereby practically eliminated.

40 45 50 In the construction shown in Figs. 4 and 5, the casing 1 is provided with an outer casing 16 and a plurality of additional breather holes or ports 17 are formed in the casing to communicate with the interior of said outer casing. These holes permit the exhaust gases to also accumulate in the interior of the casing 16 in the same manner as in the hollow core member 3.

55 Any moisture condensing in the silencer may escape by providing a draining extension 18 on

the lower opening of the spider 5, said extension communicating with openings 19 in the flanges of the casings 1 and 13, see Figs. 1 and 3. The outer casing 16 in the embodiment shown in Figs. 4 and 5 may also have a draining hole 20 for the same purpose.

The silencer or muffler as herein described is more convenient to manufacture than the previous constructions and, as previously mentioned, will be found to have greater efficiency with lower back pressure.

What I claim is:

A muffler for engine exhausts comprising a frusto-conical casing having an inlet end and an outlet end being substantially larger than said inlet end so that said frusto-conical casing has a progressively increasing diameter from said inlet end to said outlet end, a substantially cylindrical hollow core member having closed opposite conical end pieces concentrically supported within said frusto-conical casing and co-acting with the same so as to form an annular gas expansion space of progressively increasing area receiving the gases from said inlet end, and breather ports in said cylindrical core member permitting the exhaust gases to pass from said gas expansion space into said cylindrical hollow

core member, whereby said progressively increasing expansion space reduces the back pressure of the muffler and said cylindrical core member operates as a gas accumulator smoothing out the pulsating pressures of the engine exhaust, the gas pressure accumulating in said cylindrical hollow core member on the high pressure phase and being released through said breather ports on the low pressure phase, an outer casing and breather openings in said frusto-conical casing to communicate with the interior of said outer casing, said openings allowing the exhaust gases to also accumulate in the interior of said outer casing.

GEORGE BROMHEAD WALKER.
